United States Patent Office

Des. 197,049
Patented Dec. 10, 1963

197,049

DOOR STOP

Kosta E. Panopoulos, 4229 S. Grand Ave., and Lazaros
A. Zotos, 4533 Chouteau Ave., both of St. Louis, Mo.

Filed June 6, 1963, Ser. No. 75,247

Term of patent 14 years

(Cl. D10—7)

FIG. 1

FIG. 2

FIG. 4

FIG. 3

FIG. 5

FIG. 1 is a top plan view of the door stop, showing our new design;

FIG. 2 is a bottom plan view thereof;

FIG. 3 is a side view thereof, the opposite side view being identical;

FIG. 4 is a front view thereof, the rear view being identical; and

FIG. 5 is a perspective view showing the door stop in operative position on a lower, free-swinging end of a door, the door end being shown in dotted lines, for illustrative purposes only.

We claim:

The ornamental design for a door stop, as shown and described.
